(57) CLAIM

The ornamental design for an awning head with speaker, as shown and described.

DESCRIPTION

FIG. 1 is a bottom right side perspective view of an awning head with speaker, showing our new design,

FIG. 2 is a front elevational view thereof,

FIG. 3 is a rear elevational view thereof,

FIG. 4 is a left side elevational view thereof; and,

FIG. 5 is a top plan view thereof.

The broken line portions of FIGS. 1 and 3-5 are included to show unclaimed subject matter only and form no part of the claimed design.
